UNITED STATES PATENT OFFICE.

WALTER L. STARR, OF NEWARK, NEW JERSEY.

DESIGN FOR A BELT-CLASP.

SPECIFICATION forming part of Design No. 19,428, dated November 12, 1889.

Application filed August 14, 1889. Serial No. 320,764. Term of patent 7 years.

To all whom it may concern:

Be it known that I, WALTER L. STARR, a citizen of the United States, residing at Newark, in the county of Essex and State of New Jersey, have invented and produced a new and original Design for Belt-Clasps; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 In said drawings, Figure 1 represents a front plan view of a belt-clasp showing my design; and Fig. 2 is a section through line *x* of Fig. 1.

These views are deemed sufficient to fully 20 illustrate my design, the leading feature of which consists in a scalloped shell, one portion of which is attached to one part of the clasp and the other portion to the other part,

the said parts of the clasp comprising two oblong-square loops, and when the two parts 25 of the clasp are in engagement with one another it shows a complete opened shell, the outer edges of which partially overlap the said loops, as will be readily understood upon reference to the drawings, in which— 30

A A are the two loops of the clasp, and B B the two portions of the shell.

What I claim as new is—

The design for a waist-belt clasp herein shown and described, the same comprising 35 the two parts A A, forming oblong-square loops, and the parts B B, forming an opened shell, the outer edges of which partially overlap the said loops, as illustrated and set forth.

In testimony that I claim the foregoing I 40 have hereunto set my hand this 8th day of August, 1889.

WALTER L. STARR.
